CLAIM

(52) U.S. Cl. **D26/138; D25/131**

The ornamental design for a notched bar for use as a support structure in lamps and the like, as shown and described.

(58) Field of Search D6/495; D26/113,
D26/118, 155, 153, 138; 362/410, 431,
432, 464; D25/126, 127, 131

DESCRIPTION

(56) References Cited

FIG. 1 is a perspective view of the notched bar in accordance with my new design, the opposite perspective being a mirror image thereof;

FIG. 2 is a front view thereof, the rear view being a mirror image thereof;

FIG. 3 is a top view thereof;

FIG. 4 is a bottom view thereof; and,

FIG. 5 is a right side view thereof, the left side view thereof being identical.
